UNITED STATES PATENT OFFICE.

EDWIN L. SPRAGUE, OF BOSTON, MASSACIUSSETTS.

DESIGN FOR A SHOE-VAMP.

SPECIFICATION forming part of Design No. 27,585, dated August 31, 1897.

Application filed March 25, 1895. Serial No. 543,155. Term of patent 7 years.

To all whom it may concern:

Be it known that I, EDWIN L. SPRAGUE, of Boston, county of Suffolk, State of Massachusetts, have invented and produced a new and 5 original Design for Shoe-Vamps, of which the following description, in connection with the accompanying drawing, is a specification.

The drawing shows in plan view a shoe-vamp embodying my design. 10 As shown in the drawing, the leading or material feature of my design consists in a shoe-vamp having the obtuse-angle recesses or indentations 2 in the cut-out portion in the interior of the vamp, in which the instep portions are inserted, the edges of the cut-out 15 portion of the vamp adjacent to the recesses

or indentations 2 2 being made convex at 5 5 and concave at 6 6. The external sole and heel outlines 3 and 4, respectively, may be of any usual configuration. 20

Having described my invention, what I claim as new, and desire to secure by Letters Patent, is—

The design for a shoe-vamp, substantially as herein shown and described. 25

In testimony whereof I have signed my name to this specification in the presence of two subscribing witnesses.

EDWIN L. SPRAGUE.

Witnesses:

M. E. HILL,
JOS. P. LIVERMORE.
